UNITED STATES PATENT OFFICE.

FREDERICK J. LEISSE, OF ST. LOUIS, MISSOURI.

LIQUID-OPERATED JACK.

Application filed February 28, 1921. Serial No. 448,406.

To all whom it may concern:

Be it known that I, FREDERICK J. LEISSE, a citizen of the United States, residing at St. Louis, in the county of St. Louis and 5 State of Missouri, have invented certain new and useful Improvements in Liquid-Operated Jacks, of which the following is a specification.

This invention relates to liquid operated jacks and has for an object the provision of a device which may be used for hoisting vehicles or the like, especially where a wheel of the vehicle is in need of repair.

Another object of the invention is to provide a jack which may be raised or lowered with the expenditure of very little physical effort and which will quickly and effectively lift the vehicle to any predetermined height.

A further object is to provide a jack which is especially adapted for use in garages and is so constructed that its transfer from place to place may be done in a facile manner, thus making the device practical for use in being transported from one 25 vehicle to another.

The above and other objects of this invention will be more fully understood from the following description taken in connection with the accompanying drawings, 30 wherein:

Fig. 1, is a side elevational view of a jack constructed in accordance with this invention.

Fig. 2, is a horizontal sectional view of 35 one end of the base showing the latter in top plan.

Fig. 3, is a detail fragmentary side elevational view of the device showing to advantage the jack staff, the locking means 40 therefor and the means by which the lock is released.

Fig. 4, is a fragmentary side elevational view of the lock releasing means, and

Fig. 5, is a top plan view of the same.

In the drawings, in order to illustrate the application of this invention, a complete device embodying a liquid reservoir and pump is shown, although it is to be understood that these elements do not of necessity constitute an inherent part of the jack, since the reservoir and pump may constitute a source of supply and energy, respectively, which may be placed in communication with the jack per se in any desired manner.

The device illustrated consists of a base

generally designated 6, the base embodying a stand 7 at one end and a stand 8 at the opposite end. The stand 8 has mounted thereon a casing 9, which has a way leading therethrough, one end of which is in communication with one end of a liquid channel 10, while the opposite end is in communication with one end of a jack cylinder 11. A portion of the casing 9 is extended to provide a shelf 12, upon which is fixedly mounted an axle 13, the latter being equipped with wheels 14, through the medium of which the jack may be transported.

Reciprocably mounted in the cylinder 11 is a jack staff 15, the lower end of which is formed to provide a piston head while the upper end is formed to provide a vehicle engaging saddle 16 of standard design. The upper end of the cylinder is equipped with a reinforcing collar 17, upon which is mounted, at diametrically opposite points, tapering lugs 18. As shown in Fig. 1, the upper ends of the lugs terminate at approximately the upper marginal edge of the collar 17, the said upper ends being wider to provide substantial supporting surfaces.

A locking member 19 is mounted upon the staff 15 and is held in any desired position thereon by an annulus 20 which has mounted therein a set screw 21. Consequently, as is apparent the collar may be set at any desired position on the staff 15, thereby correspondingly controlling the movement of the locking member. The said locking member comprises an elongated strap having a circular enlargement formed on its upper end through which the staff 15 passes. The opposite ends of the strap are bent downwardly into parallelism with each other, each having one of its margins formed to provide ratchet teeth 22, which taper in a direction counter to the direction of taper of the lugs 18. Upon reference to Fig. 3 of the drawings, it will be noted that the portion of the locking member which embraces the staff 15 has its bore made relatively larger than the diameter of the latter, consequently, lateral movement of the locking member will be permitted to permit engagement of said locking member with or disengagement of the same from the lugs 18.

The liquid channel 10 has the opposite end, to that which is engaged with the casing 9, in communication with the base 23 of a pump 24. This pump may be of any

desired configuration and has an outlet pipe 25 leading therefrom adjacent the base 23 and in communication with the channel 10 at a point remote from the pump. In the 5 present instance a liquid reservoir 26 is arranged in parallel relation to the pump 24, and has a portion 27 depended therefrom which embraces the channel 10. The upper end of the reservoir has an extension formed 10 thereon to which one end of a link 28 is pivotally connected, the opposite end of the link being pivotally engaged with one end of a handle 29. The said handle is in 15 pivotal connection with one end of a pump piston rod 30, which latter is reciprocably mounted in the cylinder of the pump 24. A duct 31 connects the reservoir to the pump 24, and is provided with a one-way valve permitting passage of liquid from the reservoir 20 to the pump, but preventing a reverse movement of the liquid. The pipe 25 is likewise equipped with a one-way outlet valve which permits passage of the liquid from the pump 24, but prevents return of 25 the liquid into the pump through said pipe. Return of the liquid from the channel 10 is accomplished through the use of a return pipe 32, one end of the latter being in communication with said channel, 30 and the opposite end in communication with the reservoir 26.

It will be apparent from the above that when the handle 29 is moved upwardly a suction stroke of the piston will be produced, 35 thereby drawing liquid from the reservoir 26 through the duct 31 and into the pump cylinder. The downward movement of the handle will cause the liquid to be forced from the pump cylinder through the pipe 40 25 into the channel 10 and ultimately through the liquid way in the casing 9 and into the cylinder 11, causing the piston therein to be elevated which correspondingly elevates the jack staff 15. When the jack staff 45 has been elevated to the desired height, pressure on the handle 29 is released and the ratchet faces of the lock 19 permitted to gravitate into engagement with the lugs 18, thereby positively retaining 50 the jack staff from downward movement, if perchance the liquid in the cylinder 11 would be insufficient to hold the weight imposed upon the saddle 16. When it is desired to lower the jack staff pressure 55 is exerted upon the pump lever 29 to take the weight off the lock 19 and then pressure is exerted upon a releasing lever 33, the latter being connected to a valve which is mounted in the return pipe 32. The 60 lower end of said lever is in pivotal connection with one end of a releasing rod 34, the opposite end of the latter being connected to a releasing element, generally designated 35. By operating the lever 33, 65 the valve in the return pipe 32 will be

opened, thereby permitting the liquid in the channel 10 to flow through said return pipe 32 and into the cylinder 26. The releasing element 35 consists of a rigid semi-circular collar, the opposite ends of 70 which taper to edges. A resilient strap 37 is flexed into engagement with the inner periphery of the semicircular collar at diametrically opposite points. Consequently, pressure on the lever 33 will initially move 75 the semi-circular collar into a position where the tapered edges 36 thereof contact with the ratchet faces 22 of the lock 19. Continuous pressure upon said lever 33 operates 80 upon the resilient strap 37, causing the latter to be flexed so as to permit opening movement of the valve in the return pipe 32 just momentarily before the semi-circular collar is moved to a point where it will urge the ends of the lock 19 from the lugs 18. 85

It is possible that at times the liquid used for operating the jack, which is preferably oil, may seep past the piston in the cylinder 11 and consequently to catch any such leakage an overflow pipe 38 is provided, 90 one end of which is in communication with the upper end of the cylinder 11 and the opposite end in communication with the upper end of the reservoir 26, permitting this overflow to be ultimately sucked into the 95 reservoir 26 by the siphonic action of the pump.

From the above, it will be apparent that the jack staff is raised to any desired point by the pressure of the oil or other liquid 100 which may be used and that the staff will be positively locked from casual displacement. It is moreover apparent that the jack may be expeditiously lowered when desired with the expenditure of very little physical effort. 105 The construction of the device will permit quick and effective work, even on the heavier types of vehicles.

Various changes may be made in the device, especially in the details of construction, proportion and arrangement of parts within the scope of the appended claims. 110

What is claimed is:

1. A liquid operated jack including a cylinder carrying a vertically moving vehicle 115 supporting staff, means to force liquid beneath said staff to elevate the latter, means carried by the staff and engaging the cylinder to automatically lock the staff from downward movement after reaching a predetermined height, and mechanism to release said liquid and to disengage said second mentioned means, whereby the staff is permitted to gravitate under its load.

2. A liquid operated jack including a cylinder and jack staff the former of which is provided with an inlet way to permit the introduction of liquid thereinto for elevating said staff, a lug mounted on the cylinder, a locking member cooperable with said lug 120

125

to hold the staff at a predetermined height, initially neutralize the effect of said pump and 10 and locking means carried by the staff to retain said locking member in a predetermined position on the staff.

to secondarily disengage said locking means to permit the jack to gravitate under its load.

In testimony whereof I affix my signature

- 5 3. A liquid operated jack including a jack and pump in communication, said pump being operable to elevate the jack, means to automatically lock the jack at any desired height, and means operable to in-
